ATTORNEY.

UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

DOOR BUMPER.

Application filed August 27, 1923. Serial No. 659,670.

This invention relates to vehicle bodies and refers more particularly to supports for door buffers and the like.

An object of the invention is to provide a post or pillar having a reinforcing member which is preferably provided with means for supporting a plurality of yieldable buffer members and which is also preferably provided with means for effectively holding the buffer members so as to prevent accidental removal thereof from the holders.

Another object is to provide a strong and durable construction that can be manufactured at a comparatively low cost.

With the above and other objects in view the invention consists of certain novel features of construction, combination and arrangement of parts as will be more fully described and particularly pointed out in the appended claims.

In the accompanying drawing:

Figure 1 is a side elevation of a motor vehicle embodying my invention;

Figure 2 is a sectional view taken on line 2—2 of Figure 1;

Figure 3 is an enlarged fragmentary elevation of the buffers and supporting means therefor;

Figure 4 is an enlarged fragmentary elevation of the supporting means;

Figure 5 is a detail perspective view of one of the cushion members.

In the manufacture of door buffers or bumpers it is usual to provide a separate holder for each yieldable cushion member and to retain the cushion member in the holder by the frictional engagement between the edges of the cushion member and the walls of the holder.

However, it has been found that the frictional engagement alone is insufficient to retain the cushion members in the holder and oftentimes these cushion members work loose. Moreover, the cost of manufacturing the separate holders is quite an item and in addition, it is necessary to provide some suitable means upon the standard or post for attaching the holders thereto.

With the present invention all the objectionable features just referred to are entirely overcome and I preferably provide a post or standard having a reinforcing member that is provided with means for holding a plurality of cushion members and that is also

provided with means for preventing the accidental removal of such cushion members.

Referring now to the drawing in which like characters of reference designate corresponding parts throughout the several views, the numeral 1 designates a motor vehicle body having a metallic post or pillar 2 and a pair of doors 3 that are normally disposed in closed position against opposite sides of the post.

The post is preferably hollow and is preferably provided with a longitudinally extending forwardly projecting portion 4 that is preferably channel-shape in cross-section and that is preferably provided with laterally extending wings or flanges 5 which connect into the forwardly diverging sides 6 of the post. The rear wall 7 of the post is preferably formed separately and is preferably provided with marginal flanges 8 that are secured to the sides 6 adjacent to the rear edges thereof.

Located in the post, preferably adjacent to the ends thereof, are a pair of reinforcing members 9. Each reinforcing member preferably extends transversely of the post and is preferably formed of one piece of sheet metal which is preferably bent as shown in Figure 2 providing a pair of spaced pockets 10 having marginal flanges 11 that are secured to the sides of the post. These pockets preferably register with elongated openings 12 in the opposite sides of the post and preferably receive a pair of buffers 13 for the doors.

Each buffer preferably consists of a resilient cushion member 14 that preferably has a dove-tail engagement with one of the pockets, the upper and lower edges of each cushion member being preferably beveled and the top and bottom walls of each pocket 95 being correspondingly inclined. Thus, the rear ends 15 of the pockets will serve as stops for the cushion members and the inclined walls will prevent the cushion members from moving laterally or in a direction transverse to the thrust.

For preventing the cushion members from moving forwardly and thus becoming accidentally disengaged from the pockets, I preferably punch outwardly from the inner sides 16 of the pockets, suitable prongs 17 that preferably project rearwardly and that preferably spring into engagement with cor-

- respondingly shaped recesses 18 in the inner faces of the cushion members 14 when the latter are moved into position in the pockets 10. The recesses 18 formed in the cushion members are preferably identical so that it is necessary to manufacture only one form of cushion. Thus, any one of the cushion members will be readily applied to any pocket desired.
- 10 While it is believed that from the foregoing description the nature and advantages of the invention will be readily apparent, I desire to have it understood that I do not limit myself to what is herein shown and 15 described and that such changes may be resorted to when desired as fall within the scope of what is claimed.
- What I claim as my invention is:
1. In a door bumper, the combination 20 with a holder having a groove open at one end, of a cushion member slidably engageable with the holder through the open end thereof, said cushion member having a recess therein, and a member carried by the 25 holder adapted to spring into engagement with the recess to retain the cushion member in the holder.
  2. In a vehicle, a hollow post having an opening therein, of a member reinforcing 30 the post having a pocket registering with the opening, a cushion member movable through the opening in said post and slidably engageable with the pocket of said member, and a projection on the reinforcing member 35 for retaining the cushion member in the pocket.
  3. In a vehicle, a hollow post having an opening therein, of a member carried by the 40 post having a pocket registering with the opening, a cushion member movable through the opening in said post and slidably engageable with the pocket, and means formed in- tegral with said member for retaining the cushion member in the pocket.
  4. In a vehicle, a hollow post having an 45 opening therein, of a member carried by the post having a pocket registering with the opening, a cushion member movable through the opening in said post and slidably engageable with the pocket, and a prong 50 struck out from said member for retaining the cushion member in said pocket.
  5. In a vehicle, a hollow post having openings at the opposite sides thereof, of a reinforcing member for the post having 55 pockets at the ends thereof registering with said openings, cushion members extending through the openings in the post and engaging said pockets, and projections upon the reinforcing member retaining said 60 cushion members in said pockets.
  6. In a vehicle body, a hollow door post having transversely extending openings in opposite sides thereof, a sheet metal member extending transversely of said post having 65 pockets at the opposite ends thereof registering with said openings, and cushion members carried by the pockets projecting through the openings in the sides of said post.
  7. In a vehicle body, a hollow door post and a transversely extending opening in one side thereof, a metallic member extending transversely of the post having a pocket in registration with the opening, a cushion 75 member carried by the pocket extending through the opening aforesaid, a tongue stuck out from said pocket, and a correspondingly shaped recess in the inner face of the cushion member, said tongue adapted 80 to spring into engagement with the recess to retain the cushion member in the pocket.

In testimony whereof I affix my signature.
HERMAN C. MAISE.
